[57] CLAIM

The ornamental design for a container closure, as shown.

DESCRIPTION

FIG. 1 is a top perspective view of a container closure showing my new design;

FIG. 2 is a bottom perspective view thereof;

FIG. 3 is a top plan view thereof;

FIG. 4 is a cross sectional view thereof taken along line 4—4 of FIG. 3;

FIG. 5 is a front elevational view thereof;

FIG. 6 is a bottom plan view thereof;

FIG. 7 is a top perspective view of a second embodiment of a container closure showing my new design;

FIG. 8 is a bottom perspective view thereof;

FIG. 9 is a top plan view thereof;

FIG. 10 is a cross sectional view taken along line 10—10 of FIG. 9;

FIG. 11 is a front elevational view thereof; and

FIG. 12 is a bottom plan view thereof.
